UNITED STATES PATENT OFFICE.

FRANK MARION, OF BARRE, VERMONT, ASSIGNOR OF ONE-HALF TO ELWIN L. SCOTT,
OF BARRE, VERMONT.

OIL-BURNER SYSTEM AND APPARATUS.

Application filed January 28, 1926. Serial No. 84,410.

The invention relates to liquid and gaseous fuel burner systems and has for an object to effect improvements in means for maintaining such devices in constant operation where two or more sources of power are alternatively available, whereby upon failure of one, the other will be automatically set in operation in the system. It is an important aim to provide a novel mechanism 10 for accomplishing this change of power and regulating the power in such manner that in case of failure of both, the fuel supply will be cut off.

Another object is to present new construction in burner regulating devices.

Additional objects, advantages and features of invention reside in the construction, arrangement and combination of parts, as will be more readily understood from the 20 following description and the accompanying drawings, wherein,

Figure 1 is a diagrammatic view of the system;

Figure 2 is an elevational view of the 25 automatic fuel valve;

Figure 3 is a view of the valve at right angles to Figure 2;

Figure 4 is a detail sectional view of the 30 valve seat and valves.

There is illustrated a system including the main supply conduit 10 which may lead from a source of fuel under pressure or in the case of liquid fuel, either under pressure or fed by gravity. This fuel line leads 35 to the burner 11 which may be installed in a boiler or other furnace 12, as will be more particularly indicated.

In the fuel line there is incorporated an 40 automatic valve device 13, the control and function of which will be more particularly described hereinafter. Air is supplied to the burner 11 by means of a centrifugal fan or blower 14 through the conduit 14' and on the shaft of the impeller of the blower there 45 is also mounted the impeller of a water motor 15, of familiar construction, the details of which will not be illustrated, as these are generally familiar in the motor art. The shaft 16 of the water motor is also 50 directly driven by means of an electric motor 17, alternatively with the water motor 15, and a centrifugal governor 18 is mounted upon the shaft 16, the governor being of the usual construction, the details of which are 55 generally understood. The burner 11 may

conform to approved construction and practice. A drain pipe 32 leads from the burner at its lower side to drain off any excess unvaporized oil therefrom in case oil fuel is utilized. The pipe 32 runs to a suitable 60 point of disposal for the waste oil, which includes a pan 33, mounted upon a vertically movable spring-sustained support 34 which is connected to a switch 35, so that the switch will be moved to open position by the weight 65 of oil in the pan 33 after it reaches a predetermined quantity, and the element 34 is also connected to a valve 36 in the water line 37 to the water motor 15. The valve 36 is normally mounted in open position, and will 70 be closed when operated by the weight of oil in the pan 33. The switch 35 is incorporated in the main circuit to the motor 17, a hand switch 38 being also shown in the circuit for use when required.

The automatic valve device 13 also includes an electromagnet 30, connected in series in the circuit to the motor, this magnet being constructed to attract and hold an armature 41 on a lever 42 by which a valve 80 element in the device 13 is held in open position, as will be understood. The lever 42 may also carry a switch arm associated with contacts as at 43, whereby when the lever 42 is in operative relation with the 85 magnet 40, the circuit to the motor is completed thereby, as indicated by the diagram in Figure 1.

The valve device 13 comprises a body 50 having a partition 51 therethrough ported 90 on an axis at right angles to the inlet and outlet passages of the body, and having valve guiding necks 52 extending in line with the port, in which necks there are slideable the valves 53 and 54 respectively, at 95 the upper and lower sides, packings 55 being provided around the valves, which are in the form of plain rods having rounded ends to engage opposite ends of the passage through the partition 51. U-shaped frame pieces 56 are clamped upon each of the necks 52, one arm of each frame being bifurcated to embrace the neck and having clamping screws to draw the furcations of the arms together upon the neck, whereby the frames will be retained securely in adjusted positions upon the necks of the body 50. The outer arm 57 of each of these frames is apertured to receive the respective valves 53 and 54 slidably therethrough. On the 100 105 110

valve 54 there is a collar 58, and a spring 59 is confined between this collar and the arm 57, tending to close the valve. The valve extends a distance below the arm 57 and has 5 pivoted thereupon an L-shaped lever 60, having a short arm 61 adapted to wipe against the lower side of the arm 57, so that when the lever is swung upwardly, the arm 61 will bear against the arm 57 and 10 draw the valve downwardly to open position. The arm 60 is held in raised position by a link 62 connected to the extremity of the lever 42 opposite the armature 41, so that when the armature is engaged with the 15 magnet the link 62 is held in raised position, holding the valve 54 open. The link 62 has engagement with the arm 60 by means of a longitudinal slot 63 in the link, and a lateral pin 64 on the extremity of the arm 60, which 20 engages the lower end of the slot 63 and is raised thereby. The link 62 is engaged by a spring 65 tending to move it to lower position when the magnet is not energized. The arm 60 is held releasably in raised position by 25 means of a spring-pressed latch bolt engaging under a bill 66 on the lower side of the arm 60, which has an inclined wiper face on the side next the latch, so that when the arm 66 is below the latch and is moved upwardly, 30 the latch will be pressed aside for movement of the arm 60 to initial position. The latch is connected by bell cranks and links to the sliding element of the governor 18, so that at a pre-determined minimum low 35 speed, the latch will be withdrawn from beneath the arm 66, permitting the valve 54 to close.

The link 62 is extended a distance below the arm 60, and is connected to the arm of 40 a valve 68, whereby upon interruption of the electrical circuit to the motor the spring 65 will draw the link downwardly and move the arm 68 for opening of the valve 69, this valve being located in the water main to 45 the water motor, so that the motor will then be actuated without loss of time, and before the speed of the fan has dropped to such an extent as to permit the valve 54 to be closed.

50 The valve 53 at the upper side of the automatic valve device 13 is controlled by a thermostat 70 on the boiler or other furnace element heated by the burner 11. It will be understood that a pressure-responsive device is the equivalent of the thermostat. The movable element of the thermostat is connected through the agency of bell-crank levers and cables 71 to the upper end of a spring 72, the lower end of which is connected to a lever 73 pivoted in the body of the upper frame 56, its inner end within the frame being pivotally connected to a collar 74 fixed on the valve 53 and movable freely within the frame 56. By this means 55 the valve 53 is moved, increasing tempera-

ture or pressure in the boiler or furnace involving closing movement of the valve. The movement of the valve 53 may be limited by means of nuts 75 threaded thereon above and below the upper arm of the frame 56. A spring 76 is engaged with the lever 73 tending to move it to open position.

A weighted bar 77 is mounted vertically 70 slideable above the pan 33 so that at the lower limit of its movement it will engage within and rest on the pan, and this bar is held releasably in its uppermost position by a sliding latch 78, engaged in a notch in the bar and yieldingly held in engaged position by a suitable spring, as shown. A headed bolt 79 is engaged slidably in the latch 78, the sliding movement of the bolt in the latch being parallel to the direction of the movement of the latch for disengagement of the bar 77, and this bolt is connected to the 80 cable from the thermostat 70 in such manner that after movement of the cable a predetermined distance by the rise of temperature or pressure, the head of the bolt will be drawn up against the body of the latch and the latch moved thereby under continued operation of the thermostat 70, so as to finally disengage from the bar 77, downward movement of which under its weight will move the pan 33 downwardly, opening the switch 85 and opening the valve 36 so that under any operation of the fan the motive power will stop, and interruption of the electrical circuit will likewise cause cutting off of fuel, as will be understood.

In the operation of this device, the furnace being cold, the pan 33 empty, and the blower or fan at rest, in order to start the system, the parts being properly adjusted for initial operation, the switch 35 is closed and the bar 77 raised and engaged with the latch 78, the switch 78 is closed and the lever 42 moved to circuit-closing position with the armature 41 held by the magnet 40. In this position of the parts the valve 36 105 will be open, the valve 69 closed and the latch 66 retracted. Upon moving the lever 42 to operative position, however, the valve device 13 is opened at the lower side, and at the upper side is already open as far as the maximum permitted by the thermostatic control so that fuel may flow to the burner. The pilot light being properly lit in the burner 11, air and fuel will be supplied which will be ignited and burned in the 110 burner. The operation of the fan will through the governor move the latch 66 to protracted position. The burner may be preheated, if desired, or the pilot light 30, supplied with fuel independently of the valve 13, through hand valve 31, arranged to heat the burner for early vaporization of oil admitted thereto, in case liquid fuel is employed.

115 In case the circuit to the motor becomes 120 125 130

accidentally interrupted as by failure at a power plane or breakage of service lines, the link 62 will immediately drop, but momentum of the motor and the fan will continue the rotation of the shaft 16, so that the governor will not release the latch 66, and therefore the valve 13 will be still operative to permit flow of fuel for a time. The valve 68 having been opened immediately on engagement of the electrical circuit, the water motor will continue the operation of the device if water is available at proper pressure. But in case of failure of the water supply, the fan will lose momentum and the governor 18 will finally withdraw the latch, permitting the lever 60 to move downwardly, the pin 64 being free to move in the slot 63, and the fuel supply will then be cut off. In case of faulty operation of the burner while the fan is properly operated, resulting in failure of the oil to be vaporized, with consequent accumulation of oil in the lower part of the burner, this oil will drain to the pan 33 and if such drainage continues to an excessive degree the weight of the oil in the pan will finally break the circuit to the motor and close the water supply to the water motor. Then, when the speed of the fan has decreased sufficiently the fuel supply will be cut off as before indicated.

I have shown a butterfly valve 80 incorporated in the conduit 14' by which air is carried from the fan to the burner and this valve is connected to the long arm of a bell crank lever 81 having a short arm connected to the extremity of the lever 72 by which the thermostatic valve element of the automatic valve device 13 is controlled, so that when the fuel supply is cut down by the thermostat the air supply will also be correspondingly decreased, and a proper mixture afforded at all times. Air supplied to the fan may be conducted by an intake conduit 85 from the ashpit of a furnace in which the burner is incorporated, the grate being suitably covered to prevent drawing of flame or burned gases into the ashpit, and under operation of the burner the heated grate will warm the air in the ashpit so that warm air may be supplied to the fan. Suitable openings are of course provided for access of air to the ashpit as it is withdrawn through the conduit 85.

I claim:

1. A safety fuel burning system comprising a burner, a liquid fuel supply therefor, an air supply therefor including an impeller means to control the supply of fuel, two power sources, means to connect them to the impeller, means operatively responsive to

failure of one when so connected to operatively connect the other power source with said impeller, cut off means tending to cut off the fuel supply, means operatively associated with the impeller responsive to its operation to oppose the cut off means, means responsive to operation of one power source to positively hold said cut off means in inoperative position and tending to move to inoperative position, a yieldingly supported drain collector, means to drain liquid fuel from the burner to the collector, cut off means for both power sources operatively connected with said collector for operation by a predetermined quantity of fuel in said collector, an emergency responsive device responsive to conditions consequent upon an abnormal heating action of the burner, a weighted element movable into said collector, a detent therefor, and a connection between the detent and said emergency responsive device to withdraw the detent.

2. The structure of claim 1 including a fuel supply regulator and connections between the regulator and said emergency responsive device operative through initial stages of movement of the emergency responsive device.

3. The structure of claim 1 in which said emergency device is responsive to heat variations, a fuel feed regulator, operative connections between the regulator and said device responsive to heat variations including a connection yielding to movement beyond a maximum, an emergency cut off means for both power sources, and a detent having a lost motion connection with said device responsive to heat variations.

4. In a system of the character described, a burner, a fuel supply, an air supply including an electrically operated impeller, a second power source operatively associated with the impeller, cut-off means for said second power source normally in cut-off position, means tending to move the cut-off to open position, electro-magnetic means energized by the circuit to the motor to oppose movement of the power cut-off to open position, a cut-off fuel valve in the fuel supply conduit tending to move to cut-off position, a lost motion connection between the said means and the fuel valve operative in one position to prevent cut-off movement of the valve, a detent device opposing cut-off movement of the valve, and a speed responsive device operatively associated with the impeller and detent to withdraw the detent at a predetermined low speed.

In testimony whereof I affix my signature.
FRANK MARION.
